CLAIM

The ornamental design for a retail store as shown and described.

DESCRIPTION

FIG. 1 is an enlarged exterior front perspective view of a retail store showing the claimed design;

FIG. 2 is an interior bottom plan view thereof;

FIG. 3 is an interior top plan view thereof;

FIG. 4 is an interior left side elevation view thereof;

FIG. 5 is an interior right side elevation view thereof;

FIG. 6 is an interior front elevation view thereof; and,

FIG. 7 is an interior rear elevation view thereof.

The evenly dashed broken lines in the figures show portions of the retail store, as well as environmental matter, that form no part of the claimed design. The bold dashed lines in FIGS. 2, 4, and 5 are numbered reference lines used to indicate viewpoints for corresponding figures.

(Continued)

The dot-dashed broken lines in the figures show boundaries that form no part of the claimed design.
